[57] CLAIM

The ornamental design for portable combined D.C. power and compressor unit, as shown and described.

DESCRIPTION

FIG. 1 is a front perspective view of a portable combined D.C. power and compressor unit showing my new design;

FIG. 2 is a front elevational view thereof on an enlarged scale;

FIG. 3 is a plan view from above thereof on an enlarged scale;

FIG. 4 is a rear elevational view thereof on an enlarged scale;

FIG. 5 is a plan view from below thereof on an enlarged scale;

FIG. 6 is a left side elevational view thereof on an enlarged scale;

FIG. 7 is a right side elevational view thereof on an enlarged scale.

The perforations on the front of the housing are partially shown for convenience of illustration it being understood that the perforations are continuous within the defined rectangular area but for the circular element.
